UNITED STATES PATENT OFFICE.

HENRY G. ELFBORG, OF CHICAGO, ILLINOIS.

SWITCH-ROD MECHANISM.

SPECIFICATION forming part of Letters Patent No. 768,591, dated August 30, 1904.

Application filed February 8, 1904. Serial No. 192,644. (No model.)

To all whom it may concern:

Be it known that I, HENRY G. ELFBORG, a citizen of the United States, residing at Chicago, in the county of Cook and State of Illinois, have invented certain new and useful Improvements in Switch-Rod Mechanisms, of which the following is a specification.

My invention relates to that class of switch-rod mechanisms having a bracket secured to one of the switch-rails to be operated and a switch-rod secured to the other switch-rail, such members being adjustable with relation to each other and provided with a bolt or pin by means of which they, and thereby the switch-rails, may be adjusted and held in the desired relation to each other.

The principal object of my invention is to provide a simple, economical, and efficient switch-rod mechanism.

20 A further object of the invention is to provide a switch-rod mechanism comprising a bracket attached to one of the switch-rails to be operated and a switch-rod attached to the other switch-rail, with simple and efficient 25 means for adjusting such members, and thereby the rails, without being obliged to separate the parts making such adjustments.

Other and further objects of the invention will appear from an examination of the drawings and the following description and claims.

The invention consists in the features, combinations, and details of construction herein-after described and claimed.

In the accompanying drawings, Figure 1 is 35 a sectional elevation of a switch-rod mechanism constructed in accordance with my improvements; Fig. 2, a plan view thereof; Fig. 3, a view in elevation of a modification of the device, showing the switch-rod without jaws 40 and a bracket provided with jaws between which such rod is mounted; Fig. 4, a plan view of the parts shown in Fig. 3; Fig. 5, a view in elevation of the adjusting pin or bolt, and Fig. 6 a bottom plan view of the adjusting pin or bolt shown in Fig. 5.

In constructing a switch-rod mechanism in accordance with my improvements I provide a bracket *a*, which is secured to one of the switch-rails *b* by means of a bolt *c* and nut *d* or in any ordinary and well-known manner,

such switch-rail being one of a pair mounted in operative position adjacent to the main rails *e* in the ordinary manner. One end of this bracket is provided with a perforation *f*, having corrugated walls for receiving and engaging an adjusting pin or bolt, hereinafter described. A switch-rod *g* is secured to the opposite switch-rail in any ordinary and well-known manner and is provided with an upper jaw portion *h*, secured thereto by means of rivets *i* or in any desired manner familiar to those skilled in the art. The rod extends beneath such upper jaw and outward transversely beyond the switch-rail and forms what may be termed a "lower" jaw *j*, which is provided with a perforation *k* in alinement with the axial center of a similar and larger cylindrical perforation *l* in the upper jaw. The perforated end of the bracket *a* extends between these jaws in sliding engagement therewith, and the bracket and switch-rod are thus adjustable with relation to each other.

In order to provide simple and efficient means for adjusting the bracket and switch-rod, and thereby the switch-rails, with relation to each other and for firmly holding such members in operative position without removing or separating the jaws in making the necessary adjustments, I provide a pin or bolt *m*, having an upper circular neck portion *n*, fitting rotatably into the perforation in the upper jaw of the switch-rod, and, having a lower depending circular portion *o* in alinement with the axial center of such upper circular portion. The bolt is provided with an integral central eccentric portion *p*, having corrugations *q* adapted to engage the similarly-corrugated perforation in the bracket, so as to prevent the pin or bolt from turning and firmly hold the parts in position when once adjusted. The upper end of the bolt is provided with an annular head portion *r*, which engages the upper jaw of the switch-rod, and the lower end of such bolt is provided with a nut *s* in threaded engagement therewith and with a cotter *t* for holding such nut in position thereon. The lower depending circular portion of the bolt is longer than the eccentric thereof. In other words, its length exceeds the thickness of the engaging corrugated portion of the

bracket, and it will thus be seen that the eccentric portion may be raised out of engagement with the corrugated perforation in the bracket without removing the lower depending portion of the bolt or pin from engagement with the switch-rod. The switch-rod and bracket, and thereby the switch-rails, may thus be moved back and forth with relation to each other while the adjusting pin or bolt is in its raised position and in engagement with the switch-rod, and when the parts are adjusted to the desired position the pin may be lowered, so that the corrugations of its eccentric portion engage the corrugations in the bracket, as shown in Fig. 1, and thus hold the parts securely in position.

Figs. 3 and 4 show a modification of the device in which the bracket is provided with jaws *u* and *v*, between which the switch-rod is slidably mounted, such jaws being provided with perforations for receiving the circular upper and lower portions *n* and *o* of the bolt and the switch-rod being provided with a corrugated perforation for receiving the corrugated eccentric portion *p* of such bolt. The upper and lower circular portions and the central corrugated eccentric portion of the bolt being integral, such bolt may of course be raised entirely out of engagement with the bracket and switch-rod when desired and replaced after such parts have been adjusted to the desired position.

By this arrangement it will be readily seen that the adjusting nut or bolt is adapted to hold the bracket and switch-rod, and thereby the switch-rails, in any desired position with relation to each other within certain limits. When it is desirable to hold the rails at the greatest distance apart, this may be accomplished by placing the bolt in the position shown in Fig. 1. When it is desirable to bring the rails into position nearest to each other, it may be done by turning the bolt a half-revolution from the position shown in Fig. 1 and adjusting the parts to correspond. It follows as a matter of course that such rails may be adjusted to any intermediate position between these two extremes by turning the bolt a corresponding distance in either direction between these two extreme positions.

I claim—

1. In an apparatus of the class described, the combination of a bracket and a switch-rod one of such members having a perforation with corrugated walls, and a bolt extending through such bracket and switch-rod and provided with a neck portion in engagement with one of such members and having an eccentric portion in engagement with the other of such members, one of such portions of the bolt having a corrugated periphery in engagement with the member having the corrugated perforation, substantially as described.

2. In an apparatus of the class described, the combination of a bracket secured to a switch-

rail, a switch-rod adapted to be secured to the other switch-rail one of such members having a corrugated perforation, and a bolt extending through such bracket and switch-rod and provided with concentric and eccentric portions one of which is corrugated and in engagement with the member having the corrugated perforation, substantially as described.

3. In an apparatus of the class described, the combination of a bracket secured to a switch-rail, a switch-rod adapted to be secured to the other switch-rail, and a bolt mounted in such bracket and extending through such switch-rod provided with a corrugated eccentric portion in engagement with one of such members, substantially as described.

4. In an apparatus of the class described, the combination of a bracket adapted to be secured to a switch-rail, a switch-rod adapted to be secured to another switch-rail one of such members being provided with a perforation therethrough having corrugated walls, and a bolt mounted in such bracket and extending through such switch-rod provided with a corrugated eccentric portion in engagement with one of such members and having a circular portion in engagement with the other of such members, substantially as described.

5. In an apparatus of the class described, the combination of a bracket secured to a switch-rail, a switch-rod adapted to be secured to the other switch-rail one of such members being provided with a corrugated perforation, and a bolt mounted in such bracket provided with a circular neck portion and a concentric depending portion both in engagement with one of such members and having a corrugated eccentric central portion in engagement with the member having the corrugated perforation, substantially as described.

6. In an apparatus of the class described, the combination of a bracket secured to a switch-rail, a switch-rod adapted to be secured to the other switch-rail one of such members having a perforation with corrugated walls, a bolt extending through such bracket and switch-rail provided with a circular neck portion and circular depending portion in alignment with the axial center of such neck both in engagement with one of such members and having a corrugated eccentric portion in engagement with the other of such members, and means for securing such bolt in position, substantially as described.

7. In an apparatus of the class described, the combination of a bracket secured to a switch-rail, a switch-rod adapted to be secured to the other switch-rail one of such members being provided with a corrugated perforation and the other of such members being provided with jaws having perforations between which the member having the corrugated perforation is mounted, a bolt provided with upper and lower substantially cylindrical portions mounted in the perforations in such jaws and

having a corrugated eccentric portion in engagement with the member having the corrugated perforation, and means for holding such bolt in position, substantially as described.

- 5 8. In an apparatus of the class described, the combination of a bracket secured to a switch-rail and provided with a perforation having corrugated walls, a switch-rod adapted to be secured to the other switch-rail and provided
10 with jaws between which the perforated portion of such bracket is mounted, a bolt pro-

vided with upper and lower cylindrical portions in engagement with the jaws of such switch-rod and having a corrugated eccentric portion in engagement with the corrugated 15 portion of the bracket, and means for holding such bolt in position, substantially as described.
